UNITED STATES PATENT OFFICE.

WILLIAM HERBERT TOOMER, OF ELGIN, MANITOBA, CANADA.

GRAIN-CAR DOOR.

1,317,336.

Specification of Letters Patent. Patented Sept. 30, 1919.

Application filed November 26, 1917. Serial No. 203,962.

To all whom it may concern:

Be it known that I, WILLIAM HERBERT TOOMER, a citizen of the Dominion of Canada, residing at the village of Elgin, in the 5 Province of Manitoba, in the Dominion of Canada, have invented certain new and useful Improvements in Grain-Car Doors, of which the following is a specification.

My invention relates more particularly to 10 grain car doors, and the object of the invention is to provide a door of simple and inexpensive construction which will be effective to retain the grain, coal or like products without leakage from the car while 15 in transit, and which can be readily released to discharge the said products when their destination has been reached. Further objects of the invention are to provide doors of self-sustaining structure suitable for use 20 with cars of standard construction and without change of the said cars in any particular to adapt them to the doors.

Doors made in accordance with my invention may of course be used for many purposes other than that mentioned, but as their 25 most outstanding utility appears to be in connection with box or grain cars, the description to follow will be confined to that connection.

The invention in the main consists of two 30 members, similar in all respects, adapted when in position in the door opening of a grain car, to overlap on each other and on the posts at the sides of the door opening, 35 and having means whereby they are releasably united until discharge of the contents of the car becomes desirable.

The means by which the said objects are 40 attained will be found hereinafter first fully described in the following specification and then more particularly pointed out in the appended claims, reference also being had to the drawings forming part hereof, in which similar characters of reference indicate similar 45 parts throughout the various views, and in which—

Figure 1 is an outside elevation of a box car showing the door opening with the invention positioned therein.

50 Fig. 2 is a view similar to that shown in Fig. 1 but from the inside of the car.

Fig. 3 is a section taken on the line 3 in Fig. 1 and looking downward.

Fig. 4 is a view similar to that in Fig. 3, but the door being shown in the act of 55 opening outwardly to discharge the contents of the car.

Fig. 5 is an edge view of one of the door members.

Fig. 6 is a view of the outer side of the 60 same door member.

Fig. 7 is a view of the opposite or inner side of the said door member.

Fig. 8 is a sectional view through the 65 center of one of the locking members.

In the drawing 1 indicates the floor of the car having the door opening 2 with the vertical posts 3 and 4 at each side thereof connected at the top by the cross beam 5.

The door 6, the subject matter of the present 70 invention, consists of the outer and inner members 7 and 8 of similar construction and proportions throughout, the said proportions, in so far as shape and height are concerned, conforming to those of the conventional grain car door, but the length of 75 the sections being somewhat less than the width of the door opening.

The member 7 is provided with a cross bar 9 positioned back from the end of the 80 member to leave a projecting end 10 of the body portion of the member, and a second cross bar 11 at the opposite extremity of the said member, the latter being preferably secured in position by nails or other suitable 85 simple means, and the former by the bolts 12. Similarly, the said member 8 has the cross bars 13 and 14 similarly positioned and secured thereto, and leaving the projecting end 15 of the member. The cross bars 90 9 and 13 are thick and those 11 and 14 are so proportioned that when their thickness is added to that of the member to which they are secured the combined thickness is equal 95 to that of the members 9 and 13, so that when the door members are overlapped as shown in the drawings, the outer face of the cross bar 11 on the door member 7 comes flush with the face of the cross bar 13 on the member 8.

100 16 indicates a plurality of locking members pivotally secured to the face of the cross bar 13 on the door member 8 in the present instance, preferably by means of the bolts 17, the locking members being thickened at 105 their lower ends to weight them, as is best

shown in Fig. 8, and so to prevent unpremeditated rotation of the said members. The locking members are also formed with a lateral projection 18 at the top, which may 5 be struck with a hammer or other instrument to rotate the said member.

It should here be noted that the cross bar 9 on the door member 7 might be provided with locking members similar to those 16 10 on the member 8, in which case the said door members would be interchangeable as to their relative positions in the door 6 and either could be used on the outside. As it would have been a mere duplication to have shown 15 the locking members on the other door member this has not been done.

19 indicates a plate of metal secured to the faces of the projecting ends 10 and 15 of the door members preferably by means of the 20 bolts 20, the plates being let into the said members to come flush with their faces as shown in the drawings, or secured to the surfaces thereof as may be deemed most desirable. The plates 19 are perforated as at 25 21 and the perforations may continue through the thickness of the door member as is shown in Fig. 6, the said perforations providing means whereby nails or spikes 22 may be passed through and driven into the 30 posts 3 and 4 at definite points, the said points, it will be noted, being closely adjacent the extremities of the door members and the plates themselves furnishing means whereby any attempt to drive spikes through 35 into the posts at other points is baffled.

In making use of the door the member 7 is first set up with its portion 10 overlapping the inner face of the post 3 and the cross bar 9 abutting the side of the post facing 40 the door opening 2. The member 8 is next set up overlapping the inner side of the member 7 and with its projecting end 15 overlapped on the post 4 and its cross bar 13 butted against the side face of the same. 45 The length of the door member is such that when in this position the extremity of the member 7, having the cross strip 11 secured thereto, just reaches the cross bar 13 on the member 8. The locking members 16 are 50 next rotated counter-clock-wise a quarter turn by hand, thus permitting the end of the member 7 to enter behind the bar 13 and the faces of the strip 11 and cross bar 13 to come flush with each other, the locking members 55 16 then, due to the manner in which they are weighted, falling naturally into the position shown in full lines in the drawings, that is to say, across the dividing line between the strip 11 and the bar 13 and securely connecting the respective door members 7 and 8 to 60 which the said strip and cross bar are secured.

With a weight of grain against the inner sides of the members it is clearly apparent 65 that they would require no further support

and that no movement of any kind could take place to displace them. It is a fact however, that a certain proportion of shippers are not satisfied with a grain car door unless it is spiked to the car, the plates 19 70 with the perforations 22 provide the means to gratify this wish and without danger of either splitting the doors or damaging the car.

At this point it should be noted, that as 75 the outer door member is a lever of the second class, fulcrumed on the door post 3 with the load applied closely thereto through the cross strip 14 on the member 8, the power required from the locking members 16 to 80 maintain the door members bonded against outward pressure is very slight and no danger of failure at this point may be apprehended. During movement of the car or in loading it is also possible that the space 85 between the door members may become filled with grain thus assisting the door members to function as a unit.

When it is desired to deliver the contents 90 of the car, the locking members are rotated by striking their projecting portions 18 with any instrument at hand, thus releasing the members 7 which immediately assume the position shown in Fig. 4, the door member 8, urged by the pressure following and the 95 grain pouring out through the door opening. As the door members move out the spikes 22 are drawn by leverage, as is shown in Fig. 4, and they come away with the door member and do not remain to prevent the 100 placing of another door when the necessity arises.

The door members are all duplicates and they may be shipped in any number to the points required with the certainty that any 105 two of them will form a door suitable for use with any car having a door opening of standard width. Cars with door openings of special width will require doors of special dimension to match.

110 It will also be apparent from the foregoing description, that the doors may be used in many other connections aside from their utility with railway cars.

Having thus fully described my said invention, what I claim is—

115 1. A grain car door formed from a pair of interchangeable similar sections overlapped on each other for a portion of the width of the door opening and upon the door posts at the sides of the said opening, a cross bar on each section adapted to engage the sides of the adjacent door posts, plates on the portions of the sections overlapped on the door posts, perforations in the plates to permit spikes to be driven therethrough into the 120 said posts, locking members normally maintaining the sections connected and releasable to allow the said members to swing outwardly, thereby releasing the contents of the 125 130

car and withdrawing the spikes from the door posts.

2. A grain car door formed from a pair of interchangeable similar sections overlapped on each other for a portion of their length, and having their outer extremities overlapped on the door posts, plates secured to

the outer extremities of the sections, and perforations in the said plates through which spikes may be driven into the said door posts. 10

In testimony whereof, I affix my signature.

WILLIAM HERBERT TOOMER.
